Primary Examiner — Katrina A Betton*(74) Attorney, Agent, or Firm* — Stevens & Showalter LLP(57) **CLAIM**

The ornamental design for a vehicle palm rest, as shown and described.

DESCRIPTION

FIG. 1 is a perspective view of a portion of an armrest on a materials handling vehicle including a first embodiment of the vehicle palm rest taken from the front left of the armrest; FIG. 2 is a perspective view of the vehicle palm rest of FIG. 1 taken from the right side of the armrest; FIG. 3 is a top plan view thereof; FIG. 4 is a bottom plan view thereof; FIG. 5 is right side elevational view thereof; FIG. 6 is a left side elevational view thereof; FIG. 7 is a rear elevational view thereof; and FIG. 8 is a front elevational view thereof;

FIG. 9 is a perspective view of a portion of an armrest on a materials handling vehicle including a second embodiment of the vehicle palm rest taken from the front left of the armrest;

FIG. 10 is a perspective view of the vehicle palm rest of FIG. 9 taken from the right side of the armrest;

FIG. 11 is a top plan view thereof;

FIG. 12 is a bottom plan view thereof;

FIG. 13 is right side elevational view thereof;

FIG. 14 is a left side elevational view thereof;

FIG. 15 is a rear elevational view thereof; and,

FIG. 16 is a front elevational view thereof.

The broken line showings in the figures are for illustrative purposes only and form no part of the claimed design.
